CONTAINER

Isaac L. Wilcox, Fulton, N.Y., assignor, by mesne assignments, to Phillips Petroleum Company, a corporation of Delaware

Filed Aug. 20, 1963, Ser. No. 303,960
3 Claims. (Cl. 229—7)

This invention relates to containers made of sheet material such as paperboard, and has to do particularly with the attachment of the end closure to the body of the container.

Several million of such containers are used daily for the retail packaging of liquid food products, such as milk. It is most desirable that the container embody a structural arrangement whereby an end closure, particularly a top end closure may be quickly sealed in liquid tight relation and remain so sealed during handling of the filled container, and at the same time be easy and convenient to separate, or open to permit the contents of the container to be poured therefrom.

In order to render such containers, when formed of paperboard, to be entirely impervious to liquid, and to permit sterilization of the containers prior to filling, they are coated with plastic material, such for example, as polyethylene. The end closure may be quickly and conveniently permanently closed, or permanently bonded to the body of the container by the application of heat and pressure, the thermoplastic polyethylene coating also acting as an adhesive for sealing the end closures to the body of the container. However, such bonding is of a permanent nature and the overlapping, or engaging portions of the end closure, or the body and the end closure cannot be subsequently readily separated, it being necessary to puncture, tear, or otherwise mutilate the sealed parts to provide for the opening of the container to remove the contents therefrom.

In order to provide for easy opening of the sealed container in some instances, an arrangement is employed to prevent a portion of the engaging parts from heat-sealing together. This is accomplished by employing a sealed barrier of some form between confronting portions of the engaging or overlapping parts to prevent those portions of the parts from fixedly bonding together.

Also, when such containers coated with thermoplastic material are open, and the liquid contents poured therefrom, there is a tendency for the liquid to trickle, or run down the exterior of the container.

This invention has as an object a container formed of sheet fibrous material, such as paperboard coated with thermoplastic material to render the container impervious to liquids, and serving as an adhesive to seal the engaging parts of the container closure, the container of the invention embodying a unique coating arrangement, whereby an area of the engaging parts of the end closure, or the end closure and body are bonded together in a restricted area by the heat-sealing operation employed in closing the container, these engaging parts being bonded in such manner as to be entirely leak-proof, and yet the parts bonded in such area can be conveniently separated to provide a pour opening for the removal of the contents of the container.

The invention has as a further object, the employment of a coating arranged on the engaging, or overlapping parts of the container, which when the parts are separated provides for the elimination of any trickling, or run down of the contents on the outer surface of the container.

The invention consists generally of a container formed of sheet material having engaging parts coated with thermoplastic heat-sealable material for bonding the parts together. A portion of one of the parts is provided with

2

a coating of material non-heat-sealable to the thermoplastic material on said other part, the portion of said other part confronting said portion of the one part having bonded thereto in a restricted area a material heat-sealable to the coating on said portion of said one part.

The invention consists in the novel features and constructions and method hereinafter set forth and claimed.

In describing the invention, reference is had to the accompany drawings in which like characters designate 10 corresponding parts in all the views.

In the drawings—

FIGURE 1 is a view, in perspective, of a container embodying my invention.

FIGURE 2 is an enlarged, sectional view taken on line 15 2—2, FIGURE 1.

FIGURE 3 is a view, with the portion of the top closure, shown in FIGURE 2, separated from the side wall of the container.

FIGURE 4 is a plan view of the blank from which the 20 container body is formed.

FIGURE 5 is a view, in perspective, of the top corner of the container body prior to the application of the top closure.

The container illustrated in the drawings is of the general type disclosed in Patent No. 2,470,984, to R. H. Horning, et al., May 24, 1949. It includes a body formed of paperboard, or like fibrous material. The body is formed is formed from the blank shown in FIGURE 4. The blank is provided with vertically extending scores 11

30 defining side wall panels 12, 13, 14, 15 and 16. The blank is coated on both sides with thermoplastic material 20, the coating being bonded to the blank. The surface of the blank, constituting the outer surface of the container has printing applied thereto between the lines 21,

35 22. The blank is formed with an incision 23 extending lengthwise of the blank, and being spaced slightly inwardly from one side edge thereof. The body blank is severed from a web moving continuously through the printing apparatus, and the printing cylinder, simultaneously with applying the printed material between the lines 21, 22, prints a line 25 immediately above the incision line 23. This print line 25 extends laterally from one of the score lines, such as the score line 11, the print line extending approxi-

40 mately to the center of the adjacent side panels 13, 14, 45 see FIGURE 4. The purpose of the incision 23, and the print line 25 will be explained hereinafter.

The blank is folded on the score lines 11 to square tubular form with the free edge of the panel 16 overlapping the edge portion 27 of panel 12, and being heat-sealed thereto by the thermoplastic coating 20. A suitable bottom closure is bonded to the lower end of the tubular body.

After the contents has been placed in the container, a top closure is sealed to the top end of the body. This top closure is also formed of fibrous material such as 50 paperboard. The top closure is formed from a flat blank to provide a flat central area 29, dimensioned corresponding to the tubular body, and having at its periphery an upstanding flange 30 extending upwardly inside of the top portion of the body, and outwardly over the top edge of the body, and merges with a downwardly extending outer flange 31.

60 The top closure is also provided on its inner surface with a coating 33 of thermoplastic material, heat-sealable to the coatings 20 on the container body.

65 The flanges 30, 31 form an inverted channel positioned over the top edge of the container body. Heat and pressure are applied to these flanges, whereby the flanges become permanently heat-sealed and bonded to the container body by the coatings 20, 33.

70 In order to permit convenient opening of the closed container for the removal of the contents therefrom, as set forth in the Horning patent previously referred to, a

corner portion of the channel structure of the top closure was not heat-sealed to the container body. The bonding of this corner portion of the top closure was prevented by a seal barrier positioned intermediate the corner portion of the top closure flange, and the contiguous portion of the container body. Such a seal barrier may consist of a strip of sheet material 37, such as metallic foil. The foil strip 37 is heat-sealed and bonded to the inner surfaces of the closure flanges 30, 31 by the coating 33, on these inner surfaces. The opposite side of the seal barrier strip 37 has applied to it, a coating 40 of material that is non-heat-sealable to the coatings 20 on the body, and accordingly, the foil strip seal barrier prevents one corner portion of the top closure flanges from sealing to the container body. It will be apparent that the non-sealable coating 40 could be applied directly to the inner surfaces of the top closure flanges 30, 31, but that arrangement would require pattern, or spot coating on the top closure, or the body blank, if the non-sealable coating were applied thereto. It has been found in practice, that the use of the seal barrier strip 37 with the release or non-sealable coating 40 applied thereto is the more practical arrangement.

It will be understood that the seal barrier strip 37 extends about a corner portion of the container body, as the upper ends of the panels 13, 14, and preferably extends downwardly on the outer side of the body below the flange 31 of the top closure, to provide a free finger grip tab portion for assisting in moving the flange 31 outwardly from the container body, and swinging the corner portion of the top closure upwardly, as shown in FIGURE 3, to provide the corner pour opening for the removal of the contents from the container. The flat central portion 29 of the top closure may be provided with a score line 43 extending diagonally across the corner portion of the top closure, in which the seal barrier is positioned, see FIGURE 1. The arrangement described, provides a satisfactory separable top closure corner portion, which, under normal handling of the containers, remains in leak-proof engagement with the contiguous top corner portion of the container body. However, unusually rough handling of the filled container, or the application of appreciable pressure to that top corner portion of the container tends to effect premature separation between the top closure, and the container at this one sealed corner portion. If the container is of larger capacity, such as gallon or half gallon, and it is picked up by grasping the top rim of the container, the squeeze pressure at the top may cause such premature leakage. However, this arrangement in general is particularly advantageous in that it provides for easy and convenient opening of the container, and when this corner portion of the top closure is separated from the container body, and swung upwardly to provide the pour opening, that exposed top edge of the container body is sterile in that it has been previously completely protected by the top closure flanges.

By my invention, I modify the arrangement described to prevent any premature separation of the top closure from the container body without sacrificing the ease of opening the container. I obtain this advantage without incurring any increase in the cost of the fabrication of the container. The print plate or cylinder for printing the exterior of the body blank between the lines 21, 22, simultaneously applies the print line 25 to the blank. The ink used in the printing operation after drying bonds firmly to the thermoplastic coating 20 on the body blank, and after drying, this ink is heat-sealable to the coating 40 on the seal barrier strip 37, which as previously explained is bonded to the inner surfaces of the closure flanges 30, 31, by the thermoplastic coating 33. In other words, while the coating 40 on the seal barrier 37 is non-heat-sealable with the coatings 20 on the container body, the print line 25 bonded to the outer surface of the container body is heat-sealable with the coating 40 on the seal bar-

rier strip. The print line 25 is applied to a restricted area of the container body, whereby the heat seal bonding of the outer closure flange 31 to the body is only in this restricted area. This restricted area of bonding of these engaging parts is entirely sufficient to prevent any unintentional separation of the parts. On the other hand, the restricted area does not require any additional effort in the opening of the container. This is particularly true because of the incision line 23, which as previously pointed out, extends along the lower edge of the print line 25. The print line 25 is permanently bonded to the outer coating 20 of the container body, and this coating in turn is permanently bonded to the container body, all whereby when the flange 31 of the top closure is swung outwardly, the print line 25 and the coating 20 bonded thereto move with the flange causing a separation of the fibers in the outer layer of the container body.

It will be apparent that the incision line 23 aids materially in the starting of this fiber separation. This action is illustrated in FIGURE 3 of the drawings, showing the coating 20 extending above the incision 23 having been separated from the container body, leaving the same with an exposed fibrous surface, as indicated at 50. In other words, the strength of the bond between the print line 25 and the coating 20 exceeds the strength of the paper-board; when the top closure flange 31 is intentionally moved outwardly from the container body for the opening of the container, this resulting in the separation of the layer fibers to which the body coating 20 is bonded to separate from the paper in the sidewall of the container body. I have found this area of exposed fibers on the outer surface of the container body at the top edge thereof, over which the contents of the container are poured, is effective to prevent any dribbling, or run-down of the poured milk over the outer surface of the container body. While the bonding of the print line 25 to the coating 20 is sufficient to tear the coating from the container body, the incision 23 assists greatly in the more ready separation of the coating 20, and of the outer fibrous layer of the container sidewall.

The material for the coating 20 may consist of low density Alathon 16 polyethylene, manufactured and sold by E. I. du Pont de Nemours & Co., Inc., Wilmington, Delaware, Plastics Department. A material suitable for the coating 40 on the seal barrier strip 37 may consist of the following:

	Pts. By Wt.		
	A	B	C
Cellulose Nitrate, 1/2 Sec. RS	40.0	45.0	49.5
Titanium Dioxide	1.0	1.0	1.0
Toluol	20.0	24.7	24.7
Ethyl Acetate	17.2	12.4	12.4
Ethyl Alcohol	21.8	16.9	12.4
Total	100.0	100.0	100.0

The ink used in printing the exterior surface of the container body, and including the print line 25 may be a flexographic ink formulated of the following materials:

Cellulose nitrate
Pigment
Natural resins
Synthetic resins
Wax compounds
Proprietary ethyl alcohol

The coating 40 is applied wet to the seal barrier strip, and upon drying, bonds firmly thereto. The printing, including the print line 25, is applied wet to the exterior surface of the container body, and upon drying, bonds to the polyethylene coating 20. After drying, the print line 25 is heat-sealable to the coating 40. Other materials may be used for the coating 40 and the ink, if they are mutually heat sealable.

What I claim is:

1. A container formed of paperboard and having engaging parts with contacting surfaces, the entire surface of one engaging part being coated with a thermoplastic material, the major portion of the contacting surface of said other engaging part being coated with like thermoplastic material for bonding the parts together, a strip of foil bonded to the remaining portion of said other part and having bonded to its surface confronting said one part, a coating of material non-heat-sealable to the thermoplastic material on said one part, the surface of said one part confronting said foil being provided in a restricted area with a material overlying and bonded to said thermoplastic material on said one part, and being heat-sealable to the coating on said foil.

2. A container formed of paperboard, including a body member and an end closure member, said members having overlapping portions with contacting surfaces, the entire contacting surface of the overlapping portion of said body member being coated with a thermoplastic material, and the major part of the contacting surface of the overlapping portion of said closure member being coated with like thermoplastic material for heat-sealing the parts together, the remaining part of the contacting surface of the overlapping portion of said closure member having bonded thereto a strip of metal foil, the surface of said foil confronting the overlapping portion of said body member having bonded thereto a coating, including nitro cellulose material non-heat-sealable to the thermoplastic coating on the body member, the contacting surface of the overlapping portion of said body member confronting said foil having bonded thereto in a restricted area, a

coating, including nitro cellulose material, heat-sealable to the coating on the confronting surface of the foil.

3. A container formed of paperboard and having first and second parts with contacting surfaces, the entire contacting surface of said first part being coated with a thermoplastic material, a portion of the contacting surface of said second part being coated with a like thermoplastic material, said materials serving to join said coated surfaces by the application of heat and pressure, the remaining portion of the contacting surface of said second part having adhered thereto a coating of material nonheat-sealable to the thermoplastic material on said first part, the contacting surface of said first part confronting said remaining portion of said second part being provided in a restricted area with a coating overlying said thermoplastic coating on said first part and being adhered thereto, said overlaid coating being heat-sealable to the coating adhered on the said remaining portion on said second part.
